No. 1665 — Patented Oct. 21, 1868

5000 Net Wt. 1000

Des. 1665

G. A. Robinson, of New York, N.Y.
Letters Patent No. 1665, dated Oct. 21, 1862.

The schedule referred to in these Letters Patent and making part of the same,

To all whom it may concern:

Be it known that I, G. A. Robinson, of the City, County and State of New York, have invented a new and original Design for a Bottle; and I do hereby declare that the following is a full, clear and exact description of the same, reference being had to the accompanying drawings making a part of this specification, in which -

Figure 1. is a side view of a bottle of my design.

Figure 2. is a vertical section of the same, taken in the line a. a. Figure 1.

Figure 3. is an edge view of the same.

Figure 4. is a side view of the same, the reverse or opposite to that shown in Figure 1.

Dec. 1665

2

Similar letters of reference indicate corresponding parts in the several Figures.

This invention for a design consists in having the main portion or body A. of the bottle of oblong quadrilateral form in its transverse section the corners of the body forming narrow planes a, which extend the whole height of the main portion of the bottle. The front and back sides of the main portion of the bottle are both provided with a recess or sunken portion forming what may be termed "panels" b, as shown clearly in Figures 1 and 4. These panels have vertical sides c, c, and horizontal bottoms d, but their top parts are formed of two inclined parts e, e, connected by a horizontal part f. The edges of the main portion of the bottle, that is to say its narrow sides, are provided each with rectangular recesses or "panels" g, one of which is shown in Figure 3.

The upper part B. of the bottle has inclined sides h, like the roof of a cottage building each corner having a plane surface i, which are in line or coincide with the plane surfaces a, at the corners of the main portion A. of the bottle. The plane surfaces i, at the corners of the upper part B. of the bottle are of taper: from gradually diminishing from their lower to their upper ends, as shown in Figures 1, 3, and 4.

In one side of the upper part B. of the bottle there is a rectangular recess or "panel" j, as shown in Figure 4, and at the centre of the upper part B. is the neck k of the bottle.

Having thus described my invention what I claim as new and desire to secure by Letters Patent, is—

The general configuration of the parts herein shown and described to form a new and original design for a bottle.

Witnesses.

R. Hawley

J. W. Combs.
